UNITED STATES PATENT OFFICE.

ORANGE O. OZIAS AND IRA C. KOEHNE, OF DAYTON, OHIO; SAID OZIAS
ASSIGNOR TO THE COMPUTING SCALE COMPANY, A CORPORATION OF
OHIO.

DESIGN FOR A FACE-PLATE FOR SCALES.

SPECIFICATION forming part of Design No. 35,378, dated December 3, 1901.

Application filed October 30, 1899. Serial No. 735,318. Term of patent 3½ years.

To all whom it may concern:

Be it known that we, ORANGE O. OZIAS and IRA C. KOEHNE, citizens of the United States, residing in Dayton, in the county of Montgomery and State of Ohio, have produced a new and original Design for a Face-Plate for Scales, of which the following is a specification, reference being had to the accompanying drawings, forming part thereof, in which like numerals refer to like parts.

In the drawings, Figure 1 represents a front elevation of a face-plate for scales embodying our invention and design, and Fig. 2 is a sectional view thereof on line X X of Fig. 1.

The leading or essential feature of our design consists of a face-plate having a relatively wide opening therethrough, one edge of which opening is in the arc of a circle, and from near the center of the opposite edge of said opening projects a relatively long indicating-hand substantially across said opening.

In said drawings, 10 represents said circular indicator face-plate for scales; 11, the relatively wide opening therethrough; 12, the edge of said opening in the arc of a circle; and 14 represents said relatively long indicating-hand projecting from near the center of the opposite edge of said opening 11 and substantially across said opening 11.

15 15 represents a relatively small opening through the center of said face-plate.

What we claim is—

The design for a face-plate for scales, substantially as shown and described.

In witness whereof we have hereunto set our hands this 27th day of September, 1899.

ORANGE O. OZIAS.
IRA C. KOEHNE.
